US0D1062984S

(12) **United States Design Patent** (10) **Patent No.:** **US D1,062,984 S**
(45) **Date of Patent:** **** Feb. 18, 2025**

(54) **TACTICAL TRAINING TOOL**

(71) Applicant: **Zane Maltsberger**, San Marcos, CA
(US)

(72) Inventor: **Zane Maltsberger**, San Marcos, CA
(US)

(**) Term: **15 Years**

(21) Appl. No.: **29/889,498**

(22) Filed: **Apr. 13, 2023**

(51) LOC (15) Cl. **22-99**

(52) U.S. Cl.

USPC **D22/199**

(58) **Field of Classification Search**

USPC D10/104.1, 114.1, 114.9; D22/199;

D26/37, 38, 40, 42, 43, 75, 79, 137

CPC F21K 2/06; C09K 11/07; G01J 1/48

See application file for complete search history.

(57) **CLAIM**

The ornamental design for a tactical training tool, as shown and described.

DESCRIPTION

FIG. 1 is a perspective view of a tactical training tool; FIG. 2 is a front view of the tactical training tool of FIG. 1; FIG. 3 is a back view of the tactical training tool of FIG. 1; FIG. 4 is a right side view of the tactical training tool of FIG. 1;

FIG. 5 is a left side view of the tactical training tool of FIG. 1;

FIG. 6 is a top view of the tactical training tool of FIG. 1; and,

FIG. 7 is a bottom view of the tactical training tool of FIG. 1.

The broken lines are shown for the purpose of illustrating environmental subject matter and form no part of the claimed design.

1 Claim, 4 Drawing Sheets
